UNITED STATES PATENT OFFICE.

CAROLINE KITTLE, OF NORTH BERGEN, NEW JERSEY.

REGISTRY-RETURN-RECEIPT ENVELOP.

1,221,189.

Specification of Letters Patent.

Patented Apr. 3, 1917.

Application filed July 8, 1915. Serial No. 38,718.

To all whom it may concern:

Be it known that I, CAROLINE KITTLE, a citizen of the United States, and a resident of North Bergen, in the county of Hudson 5 and State of New Jersey, have invented certain new and useful Improvements in Registry-Return-Receipt Envelops, of which the following is a specification.

This invention relates to a registry return 10 receipt envelop. Its organization comprises an envelop which can be securely sealed, and which has detachably connected thereto a return card, which I designate a registry return receipt.

With my invention the request for a 15 return receipt will be obviated, and the pinning of return cards to register mail will be avoided.

Referring to the drawing which exemplifies the invention, Figure 1 represents a front view of the registry return receipt envelop; Fig. 2 shows a rear view of the envelop; Fig. 3 represents a plan view of the blank with the requisite sealing or gumming material before being folded into shape; Fig. 4 shows an end view of the invention with its partially formed pocket; Fig. 5 shows an end view of the envelop with its pocket completed and sealed; Fig. 6 is an 20 end view of the completed envelop with its return receipt or card still attached and Fig. 7 represents an end view of the envelop after the return receipt or card has been detached.

The envelop of the invention comprises 25 the main sections 20 and 21. The section 20 side portions has formed therewith the flaps 25 and 26. The latter flap is gummed at its side portion 27. The section 21 has formed therewith the gummed tongue 30 30 and is gummed at its side portions 31 and end portion 33. With the section 20 is formed the return card 35 with the gummed tongue 36. Perforations 38 are formed on the crease between the section 20 and the return card 35 and an opening 40 is formed in said return card. The outside face B of the return card has printed thereon the name and address of the sender and such other matter as may be necessary as for instance 35 the following.

This card must be safely and correctly made up and addressed at the post office where the article is registered. The postmaster who delivers this registered article

must see that this card is properly signed, 55 legibly postmarked and mailed to the sender without envelop or postage.

The first step to form the envelop is to fold the section 21 over the section 20 and seal the portions 31 to the side portions of 60 the section 20, which forms the pocket 45 of the envelop. Next the letter or other matter to be mailed is placed in the said pocket, and the end portion 33 is sealed or 65 gummed to the top portion 46 of the section 20. Then the tongue 30 is brought through the opening 40 and gummed to the outside front face of the envelop. Now the flap 25 is folded and located upon the outer face of the section 21, after which the flap 26 is 70 folded on the outer face of the section 21 and the portion 27 is gummed to the flap 25. The return card 35 is then folded to be located over the flaps 25 and 26 and the tongue 36 is brought over and gummed to the outer 75 face of the section 20.

The registry return receipt envelop is now ready for use. On the outside face A of the envelop and section 20 is written the name and address of the addressee as indicated 80 in Fig. 1. On the inside face D of the card 35 is printed the form for registry return receipt, with date of delivery and signature or name of addressee or signature of addressee's agent and such other information 85 as may be necessary, as for instance, the following:

Received from the postmaster registered article, the original number of which appears on the reverse side of this card. When 90 delivery is made to an agent of the addressee, both addressee's name and agent's signature must appear on this receipt.

A registered article must not be delivered 95 to any one but the addressee or the person in whose care it is addressed, except upon addressee's written order or a written order from the sender, transmitted by the mailing postmaster and duly verified.

When the above receipt has been properly 100 signed it must be postmarked with the name of delivery postoffice and actual date of delivery and mailed to its address, without envelop or postage.

When the envelop is delivered to the addressee the return card is detached, signed 105 by the addressee or his agent and mailed to the sender. By this means the registered

envelop has been safely delivered to the addressee and the return card is mailed to the sender without danger or loss.

Having described my invention what I desire to secure by Letters Patent and claim is:

An envelop comprising a pair of sections, one of said sections having a notch adjacent its edge and the other section having a tongue, the sections being folded over and secured together to form a pocket and the tongue entering the notch and secured to the adjacent section, a pair of flaps extending

from the opposite edges of one of said sections and folded over the pocket with their ends fastened together and a flap detachably connected to said notched section, said last mentioned flap having a tongue. 15

Signed at North Bergen in the county of Hudson and State of New Jersey this 23rd day of June A. D. 1915.

CAROLINE KITTLE.
